United States Patent Office

Des. 230,244

Patented Feb. 5, 1974

230,244

ELECTRIC BLENDER OR SIMILAR ARTICLE

Jack W. Kalbfeld, Old Bethpage, N.Y., assignor to Van Wyck International Corporation, New York, N.Y.

Filed June 29, 1972, Ser. No. 267,618

Term of patent 14 years

Int. Cl. D7—04

U.S. Cl. D7—154

FIG. 1 is a perspective, viewed from the front of an electric blender or similar article, showing my new design; FIG. 2 is a perspective, viewed from the rear thereof; and

FIG. 3 is a top plan view thereof.

I claim:

The ornamental design for an electric blender or similar article, as shown.
